UNITED STATES PATENT OFFICE.

STEVAN KOVACHEVIC, OF PITTSBURGH, PENNSYLVANIA.

ZINC-RETORT CLEANER.

Application filed July 25, 1923, Serial No. 653,766. Renewed April 18, 1925.

To all whom it may concern:

Be it known that I, STEVAN KOVACHEVIC, a citizen of the United States, residing at Pittsburgh, in the county of Allegheny and

5 State of Pennsylvania, have invented new and useful Improvements in Zinc-Retort Cleaners, of which the following is a specification.

This invention relates to means for cleaning out retorts, and more particularly to what I term a zinc retort cleaner.

One of the main objects of the invention is to provide a machine of comparatively simple construction and operation which 15 will act to quickly and effectually clean out the tubes of zinc retorts and similar structures. A further object is to provide a machine of this character which may be readily manipulated by a single operator and can be quickly and easily moved into 20 position for cleaning out the retort tubes. A further object is to provide simple and efficient means for adjusting the cleaning and scraping members. Further objects 25 will appear from the detail description.

In the drawings:—

Figure 1 is a top plan view of the cleaner;

20 Figure 2 is a transverse sectional view; Figure 3 is a side view partly broken away;

25 Figure 4 is a diagrammatic view of the means for supplying air to the various cylinders;

Figure 5 is a fragmentary top plan view 30 of one of the blocks and associated parts for operating the shovels;

Figure 6 is a fragmentary top plan view 35 of the cross-head and associated parts for operating the scrapers;

Figure 7 is a front view of the machine.

My cleaner is intended to be used in connection with zinc retorts of a known type in which the ore is placed in inclined tubes 45 arranged in a plurality of vertical series, these tubes opening onto a track which extends parallel with the front of the furnace or retort, this track providing means for adjusting or feeding the cleaner along the retort.

50 The cleaner includes a main supporting frame 1 constructed and braced in any suitable manner. Shafts or axles 2 and 3 are rotatably mounted in frame 1 at the front and back thereof, wheels 4 being secured on the ends of these axles, these

wheels being adapted to travel upon the rails of a track extending parallel with and adjacent to the retort to be cleaned. A gear 5 is secured on axle 3 and meshes with 60 a pinion 6 secured on the armature shaft of an electric motor 7 supported above and adjacent to axle 3. Current is supplied to this motor in any suitable or preferred manner, this providing simple and efficient means whereby main frame 1 may be moved in either direction along the track.

A movable frame 8 is mounted transversely of the main supporting frame 1, frame 8 extending between uprights 9 70 which extend from each corner of main supporting frame 1. Screw bars 10 are mounted in uprights 9 and threaded through sleeves 10^a secured to frame 8, the lower ends of these bars being seated in bearing blocks 11 secured in the lower ends of the uprights. The upper ends of the uprights 9 are connected by a rectangular top brace frame 12 and the bars 10 pass through this frame. Bevel gears 13 are secured on the 75 upper ends of rods 10 and mesh with bevel pinions 14 secured on the ends of counter shafts 15 rotatably supported in bearing brackets 16 secured to top frame 12. A gear 17 is secured on one of the shafts 15 80 and meshes with a pinion 18 secured on the armature shaft of an electric motor 19 mounted on frame 12, current being supplied to this motor in any suitable or preferred manner. This provides simple and 85 efficient means whereby the frame 8 may be readily adjusted vertically between uprights 9 of the main supporting frame 1.

Blocks 20 are slidably mounted, by means 90 of tongue and groove connections, in guide members 21 of approximately semi-circular cross-section, these members being supported by brackets 22 in parallelism with and arranged longitudinally of the movable frame 8. A gear member or quadrant 23 is secured to each guide member 21 and is engaged by a worm 24 of a worm shaft 25 95 rotatably mounted in bearing blocks 26. A bevel gear 27 is secured on shaft 25 and meshes with a bevel gear 28 secured on an adjusting shaft 29 rotatably mounted longitudinally of frame 1. At the rearward end of adjusting shaft 29 I provide a vertically extending rod 30 on the upper end of which is secured a crank 31, this rod being 100 operatively connected, at its lower end, to shaft 29 by mitre gearing 32. The crank

31 is preferably positioned adjacent to an operator's chair or seat 33 secured upon a bridge 34 which extends transversely of frame 1. This bridge also supports a control board 35 upon which are mounted suitable switches, valves, etc., for controlling the operation of the machine in a manner to be described. By turning rod 30, by means of crank 31, guide members 21 may be turned in their supporting brackets 22 for adjusting the blocks 20 relative to the horizontal. A shovel 36 is connected to each block 20 by means of a shank 37 extending rearwardly from the head or scoop portion of the shovel, this shank being pivotally secured at its rearward end, between two spaced ears 38 extending forwardly from block 20. Shank 37 is supported upon a grooved roller 39 mounted in a rectangular frame 40 provided at the lower end of each side bar with an extension 41 slideable through a transverse brace strip 42 which connects the forward portions of lower side strips 43 of frame 8. The frame 40 is connected, at its upper end, at 44, to an arm 45 secured on a shaft 46 rockably mounted in uprights 47 secured to the sides of frame 8 at the forward end thereof. An arm 48 is secured on shaft 46 between arms 45 and is pivotally secured, at 49, to the forward end of a pitman 50 the rearward end of which is pivotally secured at 51 to a piston rod 52 secured to a piston operating in a cylinder 53 mounted upon a cross strip 54 secured to the upper side strips 55 of frame 8. By admitting pressure fluid, such as compressed air, to cylinder 53 so as to move the piston within the cylinder in proper direction frame 40 may be readily raised or lowered so as to vary the slant or inclination of the shovel 36 as desired. Block 20 is connected by a pitman 56 to the forward end of a piston rod 57 secured through a piston (not shown) operating in a cylinder 58. By supplying compressed air to this cylinder at one end thereof and exhausting the air from the other end of the cylinder, the piston, and consequently piston rod 57 may be adjusted in either direction desired thus projecting or retracting the shovel 36 as required. This provides simple and efficient means whereby the inclination of the shovel may be readily adjusted and the shovel can be projected or retracted as circumstances may require.

55 A scraper 59 is provided above shovel 36, this scraper being of approximately circular outline and hinged at 60 to a pitman rod 61 which is pivoted at 62 to piston rod 63 which is secured through a piston (not shown), operating in a cylinder 64 mounted on a cross-head 65 slidably mounted on support and guide strips 66 supported by brackets 67 secured to frame 8. Cross-head 65 is connected to a piston rod 68 secured through a piston operating in a cylinder 69 mounted

on the rearward portion of frame 8, suitable means being provided for admitting compressed air to the cylinder at either end thereof and exhausting air from the other end of the cylinder. Scraper 59 is provided with a depending lug 70 which is pivotally secured at 71 to an operating rod 72 which is pivotally secured at its rearward end, at 73, to cross-head 65. As will be understood, I provide suitable means for admitting air to cylinder 64 at either end thereof and exhausting air from the other end of the cylinder for the purpose of projecting or retracting pitman 61 so as to adjust scraper 59 about pivot point 71. Rod 72 rests upon a roller 73 mounted in frame 40 above roller 39 so that by adjusting the frame the inclination of rod 72 is varied as desired. This provides very simple and efficient means whereby the scraper can be projected and retracted and can also have its inclination varied and can be adjusted relative to the horizontal to suit circumstances.

As will be understood, any suitable or preferred means may be employed for operating the pistons in the various cylinders. In Figure 4 I have indicated diagrammatically one arrangement whereby compressed air can be supplied to either end of any of the cylinders, selectively, and exhausted from the other end thereof. This means includes a compressed air supply hose 74 which supplies air under pressure to a manifold 75 positioned adjacent to control board 35. Manifold 75 communicates with valve casings in which are mounted three-way valves 76. Pipes 77 extend from the casings of the respective valves and communicate with the ends of the respective cylinders so that, by turning any of the valves 76, selectively, in proper direction, compressed air may be admitted to one end of the cylinder controlled by that particular valve, and the air exhausted from the other end of the cylinder.

For supplying current to the motors 7 and 19 I provide an electric cable 78 which may be connected to any suitable source of electrical energy, this cable extending to the control board 35 on which is mounted two switches 79 of any suitable or preferred type, one of these switches being connected by a wire 80 to a resilient contact arm 81 secured on frame 8, this arm pressing against a contact strip 82 secured on one of the uprights 9, which strip is connected to one pole of motor 19 the other pole of which may be grounded in any suitable or preferred manner as through frame 1. The other switch 79 is connected by a cord 83 to a resilient contact arm 84 similar to arm 81, arm 84 being also carried by frame 8 and contacting with a strip 85 secured on one of the uprights 89. Strip 85 is connected to one pole of motor 7 the other pole

of which may be grounded. This provides simple and efficient means whereby the operation of the various parts of the machine, as well as the travel of the machine, may be readily controlled. In use, the machine travels along the track parallel with the retort and is stopped in position with the shovels and scrapers in the vertical planes of two adjacent series of tubes. Frames 40 are then adjusted by means of cylinder 53 and the parts associated therewith so as to raise or lower the shovels and the scrapers, as the case may be, and adjust the same at the same inclination as the inclination of the tubes. After this has been done, ordinarily, frame 8 is adjusted vertically so as to bring the shovels 36 into alignment with the tubes to be cleaned, after which the shovels are projected by admitting air to the cylinders 58, the shovels being independently operated. As the shovel is projected into the tube it serves to effectually scrape away from the tube and loosen the residuum of the ore so as to thoroughly scrape and clean the inner surface of the tube. By turning member 21 by means of crank 31 and the parts associated therewith, thorough scraping and cleaning of the tube is assured. After the material within the tube has been thoroughly loosened and removed from the inner face of the tube, the shovel is withdrawn after which frame 8 is lowered so as to bring the scraper 59 into alignment with the tube and air is admitted to cylinder 69 at the rearward end thereof thus projecting both of the scrapers into the tubes with which the scrapers are aligned. When the scrapers are projected into the tubes they are in substantially horizontal position, as in Fig. 3. After the scrapers have been projected into the tubes, air is admitted to the cylinders 64 so as to project pitmans 61 turning the scrapers into substantially vertical position so that the scraping edges 59^a thereof contact with the inner surface of the lower portion of the tubes. By admitting air to the forward end of cylinder 69 and exhausting the air from the rearward end of this cylinder, the scrapers are withdrawn from the tubes and act to thoroughly scrape out or remove all of the materials which have been previously loosened by the shovels 36. In some cases, as when using new tubes, the residuum of the ore does not adhere to the inner surface of the tube so that it is not always necessary to use the shovel 36. For this reason the shovels are independently operative, as above noted. I have shown the machine as adapted for cleaning two tubes of adjacent series of tubes, at a time, but it will be understood that the machine can be constructed to clean any number of tubes simultaneously desired and practicable. The material which is removed from the tubes falls

into an opening or pocket which extends along the foundation wall of the retort closely adjacent to the ends of the tubes; this ash pocket, as it is termed, communicating with a tunnel which extends beneath the retort. 70

To protect the operator of the machine against the intense heat encountered adjacent to the retort when cleaning out the tubes, I provide shields at the front and 75 sides of the machine. At each side of the main frame 1 I provide a shield 86 of substantially rectangular shape, this shield including a plurality of superposed horizontally extending troughs 87 so disposed that 80 water which flows into the topmost trough will cascade from the top of the shield to the bottom thereof so that all of the troughs are filled and a sheet of running water is provided extending from the top to the 85 bottom of the shield. Similar shields 88 are provided at each side of frame 8 at the rearward portion thereof, and a smaller shield 89 constructed similarly to the shields 86 is provided at the front of frame 8, shield 90 90 being supported by uprights 47. Water is supplied to the shields 86, 88 and 89 by means of a pipe frame 90 mounted upon base frame 12 and provided with discharge nozzles positioned to discharge water into 95 the topmost troughs of the respective shields, water being supplied to frame 90, from any suitable source of supply by means of flexible hose 91. Preferably, though not necessarily, I provide inclined 100 troughs 92 positioned to receive the water discharged from the respective shields, these troughs also being positioned to discharge this water at the front of the machine into the ash pocket previously referred to. The 105 water which flows from the front shield 89 flows over the scrapers and the shovels and acts to cool the same so as to prevent twisting or warping thereof.

What I claim is:—

1. In a machine of the character described, a main supporting frame, a supplemental frame, means for adjusting said supplemental frame vertically in the supporting frame, shovels carried by the supplemental frame, means for projecting and retracting said shovels, scrapers carried by said supplemental frame, means for projecting and retracting said scrapers, and means for adjusting the scrapers and the shovels at an inclination. 115

2. In a machine for cleaning out the tubes of retorts, a shovel member adjustable into alignment with a tube to be cleaned, means for projecting and retracting the shovel member and for rotating it for detaching materials adhering to the inner surface of the tube, a scraper adjustable into alignment with the tube, means for adjusting the scraper into substantial parallelism with 120 125 130

the tube for insertion thereinto and for adjusting said scraper into position to extend substantially diametrically of the tube after the scraper has been inserted thereinto, and 5 means for projecting and retracting said scraper for inserting it into the tube and removing therefrom materials detached from the tube by the shovel.

3. In a machine for cleaning out the tubes 10 of retorts, a shovel member adjustable into alignment with a tube to be cleaned, means for rotating said shovel member and for projecting and retracting it for detaching materials adhering to the inner surface of 15 the tube, a scraper adjustable into alignment with the tube, means for adjusting the scraper into substantial parallelism with the tube and into position at an angle to the tube, means for projecting and retracting 20 said scraper, and means for adjusting the shovel and the scraper vertically.

4. In a machine for cleaning out the tubes 25 of retorts, a shovel member, a scraper disposed in vertical alignment with and parallel to the shovel member, means for adjusting the scraper and the shovel member at an inclination to the horizontal, means for projecting and retracting the shovel member and for rotating it, and means for projecting and retracting the scraper for inserting it into a tube and withdrawing 30 therefrom materials which have been detached from the inner surface of the tube by the shovel member.

35 5. In a machine for cleaning out the tubes of retorts, a shovel member, a scraper disposed in vertical alignment with and substantially parallel to the shovel member, means for adjusting the shovel member and 40 the scraper at an inclination to the horizontal, means for raising and lowering the shovel and the scraper, means for rotating the shovel and for projecting and retracting the shovel for detaching from the inner surface 45 of a tube into which the shovel is inserted materials adhering to the tube, and means for projecting and retracting the scraper for inserting it into a tube and withdrawing therefrom materials detached 50 from the tube by the shovel.

55 6. In a machine of the character described, a frame, a shovel slidably supported in the frame, means for projecting and retracting said shovel, means for turning the shovel about its longitudinal axis, a scraper mounted adjacent to the shovel and disposed to remove from a tube materials detached from the tube by the shovel, and means for projecting and retracting said scraper.

60 7. In a machine of the character described,

a frame, a shovel including a rearwardly extending shank, means for slidably supporting said shank, a guide member mounted on the frame for turning movement about a horizontal axis, means for adjusting said 65 guide member, a block slidably mounted in the guide member and connected thereto for turning movement with said guide member, said shank being pivoted to the block, means for adjusting said block longitudinally of 70 the guide member, a scraper slidably supported in the frame adjacent to and in substantial parallelism with the shovel for removing from a tube materials detached from the inner surface of the tube by the shovel, 75 and means for projecting and retracting said scraper.

8. In a machine of the character described, a frame, a cross-head slidably mounted in the frame, means for operating said cross-head, an operating rod secured at its inner end to the cross-head, means for slidably supporting said rod, a pitman rod, a scraper hinged to the outer end of said pitman rod, 80 said scraper being pivotally secured beyond 85 its hinge to the outer end of the operating rod, and means carried by the cross-head and connected to the pitman rod for projecting and retracting the same.

9. In a machine of the character described, a main supporting frame, a supplemental frame mounted on the main frame, means for adjusting said supplemental frame vertically in the main frame, a block slidably mounted in the supplemental frame, means for adjusting said block longitudinally of 90 said supplemental frame, an adjusting frame carried by the supplemental frame, means for adjusting said adjusting frame vertically, a shovel including a shank slidably mounted through the adjusting frame and pivoted at its inner end to the block, a cross-head slidably mounted in the supplemental frame above the block, means for operating the cross-head, an operating rod 95 slidably supported through the adjusting frame and pivoted at its inner end to the cross-head, a scraper pivoted to the outer end of said rod, a pitman rod hinged at its outer end to the scraper in rear of the pivotal connection between the same and the operating rod, and means carried by the cross-head and pivotally connected to the inner end of the pitman rod for projecting and retracting the same independently of 100 movement of the cross-head.

In testimony whereof I affix my signature.

STEVAN KOVACEVIC.
